UNITED STATES PATENT OFFICE.

JOHN OTTO, OF CHICAGO, ILLINOIS.

SAFETY-STOP FOR ELEVATORS.

1,264,847.

Specification of Letters Patent. Patented Apr. 30, 1918.

Application filed March 24, 1917. Serial No. 157,179.

To all whom it may concern:

Be it known that I, JOHN OTTO, a citizen of the United States, residing at Chicago, in the county of Cook and State of Illinois, have invented certain new and useful Improvements in Safety-Stops for Elevators, of which the following is a specification.

This invention relates to a safety stop for elevators and has for its primary object to provide simple, positive and automatic means for arresting the downward movement of the elevator car if, through accident to the lifting mechanism loss of control by the operator, or from some other cause, an unsafe speed is attained by the car. These results are attained by providing the car with locking levers that, when released, engage stops fixed at the sides of the elevator shaft, said levers being normally maintained out of engagement with the stop by the upward pull of the lifting cables attached to the car.

With the above as the principal object in view, the invention consists in the novel construction, combination, and arrangement of parts hereinafter described, pointed out in the appended claims, and illustrated in the accompanying drawings, in which

Figure 1 is a vertical transverse section through the center of the upper portion of the elevator car with the improved safety stop in position thereon,

Fig. 2 is a plan view partly in section of a portion of the car and safety stop mechanism,

Fig. 3 is a view similar to Fig. 1 showing the stop mechanism in operation and supporting the car against downward movement,

Fig. 4 is a perspective view of a detail of the invention.

In the drawings, 10 indicates an elevator car of the usual construction movable vertically in a shaft 11. A cable 12 is attached to the top of the car and serves to raise and lower the car in the shaft. The cable 12 is attached to a block 13 supported above the top of the car in the center thereof by means of four parallel rods 14 bolted to the top of the car and rising vertically thereover. In the present instance two plates 15 in parallel relation are secured to the top of the block 13 and extend at their ends beyond the sides thereof. Like plates 16 are fastened to the bottom of the block under the plates 15 and through the projecting ends

of these plates are formed openings for the passage of the rods 14. Surrounding each rod 14 between the upper plates 15 and heads 17 on the upper ends of the rods are coil springs 18 by means of which the car is yieldingly supported and which should the cable 12 break, or be suddenly released, will force the block 13 downwardly and cause the stop mechanism to operate in the manner hereinafter described.

Fixed against each side wall 19 of the shaft 11 in the center line of the elevator car 10 is a rack 20 extending from the top to the bottom of the shaft, each rack meshing with a gear wheel 21 journaled in brackets 22 bolted to the side and top of the car 10 at the upper corners thereof, the gear wheels 21 extending through slots 23 in the sides of the car. Upon each side of the gear wheel 21 concentric therewith is an elongated hub 24 from the peripheries of which hubs there project a plurality of tangential lugs or teeth 25 adapted to be engaged under certain conditions by upwardly projecting fingers 26 formed on the lower terminals of sliding stops 27, the upper ends of which stops are connected to the lower ends of chains, cables or other flexible connectors 28 that pass upwardly through openings 29 in the top of the car and are attached to the outer ends of the plates 15. Each stop 27 is supported upon an inclined plate or slide-way 30 fastened at its upper end to the top of the car and extending downwardly and outwardly at an angle toward the side thereof, the lower end of said plate or guide way being curved and having a longitudinal slot 31 formed therein below the stop 27, through which slot a hook 32 extends downwardly from the stop and has connected thereto one end of a spring 33, the opposite end being attached to the side of the car. These springs tend normally to draw the stops downwardly and their fingers into position to engage the lugs or teeth 25 on the hubs 24 and stop the rotation of the gears 21 and the downward movement of the car 10. The fingers 26, however, are maintained out of the path of movement of the teeth 25 by the chains 28 and only when said chains are loosened can the stops 27 be drawn into engagement with the teeth 25 by the springs 33.

Pivotal connected to the front end of the block 13 above the elevator car are the upper ends of two lever arms 34, these arms

being journaled on a common pin 35, and extending downwardly at an angle through a slot 36 in the top of the car and through slots 37 in the sides of the car, a short distance below the top. The lower ends of these lever arms are forked, a short toe 38 extending horizontally through the slot 37, while a longer toe 39 projects downwardly within said slot. Similar lever arms 34 are 10 pivotally mounted on a pin 35 at the rear end of the block 13. Just within the car the lower ends of the lever arms pass between horizontal rollers 40 which support the arms and serve to guide them in their 15 longitudinal movement.

In front and in rear of each rack 20 and in line with the lever arms 34 are vertical ratchet bars 41 secured to the side walls 19 of the elevator shaft and adapted to engage 20 the toes 38 on the lever arms when the car is to be locked against downwardly movement. The ratchet bars 41 are provided on their sides facing the car 10 with angular teeth 42, the upper sides of the teeth being 25 horizontally disposed to provide a firm engagement therebetween and the toes of the lever arms 34.

In use, the attachment is applied to an elevator as shown in Figs. 1 and 2 and under 30 normal conditions the parts will be retained in the position shown in Fig. 2, that is to say, the block 13 will be raised a short distance above the top of the elevator, thereby placing the springs 18 under compression. 35 The chain 28 by this movement of the block will also be drawn upwardly and cause the stops 27 to move beyond the teeth or lugs 25 on the hubs of the gear wheels 21. By the upward movement of the block 13 the lever 40 arms 34 pivoted thereto will also be raised a short distance and their lower ends traveling between rollers 40 drawn inwardly, thereby freeing the toes 38 from any chance of engagement with the teeth 42 of the 45 ratchet bars 41. As the car is raised and lowered, the gear wheels 21 rotate freely but if through some accident the cable 12 is broken or suddenly released, the springs 18 will immediately force the block 13 downwardly upon the top of the car, thereby 50 slackening the chains 28 and permitting the springs 35 to draw the stops 27 downwardly so that the fingers 26 thereon will engage with the teeth 25 on the hubs 24 and tend to 55 stop the rotation of the gear wheels and the downward movement of the car. At the same time the pivot pins 35 of the lever arms 34 moving downwardly with the block 13 forces outwardly beyond the sides of the car 60 10, the lower ends of said lever arms to such a distance that the toes 38 thereon will be forced into engagement with the ratchet bars

41 and the teeth thereon locking with said toes positively stop the downward movement of the car before the same has attained a 65 greatly increased speed. The car will thus be held against falling until the cable 12 has been fixed or a temporary cable secured to the block 13 and the latter lifted again into 70 position shown in Fig. 1.

What I claim is:

1. In a safety stop for elevators, the combination with a car and a lifting cable for said car, of a block secured to the lower end of the cable and movably connected to said car, guiding means attached to the top of the car for directing the movement of said block in a vertical direction, rack bars connected to the sides of the elevator shaft, gear wheels pivotally mounted in the top of the car in 80 engagement with said rack bars and having laterally extending hubs, teeth projecting from the hubs of said gear wheels, stops on each side of said car, each stop adapted to normally engage a tooth projecting from 85 the hub of the gear wheel on the same side, a spring connected to each of said stops for holding it in engagement with said tooth, a slideway for supporting each of said stops, and flexible connections between the stops 90 and the block.

2. In a safety stop for elevators, the combination with a car and a lift cable for said car, of a block secured to the lower end of the cable and movably connected to the car, 95 guiding means attached to the top of the car for directing the movement of said block in a vertical direction, resilient means connected to said guiding means and tending at all times to force the block in a downward 100 direction, rack bars connected to the sides of the elevator shaft, gear wheels pivotally mounted in the top of the car in engagement with said rack bars and having laterally extending hubs, teeth projecting radially from 105 said hubs, an inclined slideway below each of said hubs, the ends of said slideways being connected to the top and the adjacent side walls of the car, the lower end of each slideway being curved under the hub, a locking stop mounted on each slideway and adapted to engage the teeth of the hub above the same, a flexible connection between each locking stop and said block, and a spring 110 connected to each locking stop for normally 115 maintaining said stop in engagement with a tooth on said hub.

In testimony whereof I affix my signature in presence of two witnesses.

JOHN OTTO.
